UNITED STATES PATENT OFFICE.

ARTHUR C. HEMPEL, OF DETROIT, MICHIGAN.

TOY.

Application filed May 20, 1925. Serial No. 31,565.

To all whom it may concern:

Be it known that I, ARTHUR C. HEMPEL, a citizen of the United States, residing at Detroit, in the county of Wayne and State of Michigan, have invented certain new and useful Improvements in Toys, of which the following is a specification.

This invention relates to a toy, and has for its object the construction of a device which will automatically open at a predetermined time to discharge the contents of the device. This device is more particularly adapted for use as a toy which may be thrown in the air by children, and when the same attains the desired height it will open and discharge a parachute which will open and gently fall to the ground.

The construction of this parachute is such that the same positively opens but may be readily collapsed and reinserted in the holder for repeating the operation. Such a construction as I have described may be employed with a plurality of parachutes or other articles.

The device or toy is very cheaply and quickly made and may be operated with very little trouble, and yet the same is positive in its operation and provides a very entertaining toy for children.

In the drawings:

Fig. 1 is a perspective view of the toy when closed.

Fig. 2 is a perspective view of the toy when opened, showing a plurality of parachutes positioned therein.

Fig. 3 is an edge elevation of the toy showing the same in the process of opening.

Fig. 4 is a perspective view of the parachute showing the initial step in opening the same.

Fig. 5 is a perspective view of the parachute fully opened.

Fig. 6 is a detail of the blank used in making the parachute.

This toy consists of a hook-shaped closure member which consists of a pair of relatively stiff flat members, *a* and *b*, and which are hinged together, as at *c*. A spring *d* yieldingly forces these two members *a* and *b* apart so as to open the closure. Integral with the closure halves, or secured thereto by a separate means, as I have shown in the

drawings, are the arms *e*, which are so positioned as to lie adjacent to each other when the halves *a* and *b* are brought together.

I preferably place one or more collapsible parachutes *f* in this closure and when the two halves are brought down together these parachutes are held therebetween. I provide a means for temporarily holding this closure in an enclosed position by securing an elastic member *g* to one of the arms as at *h*, and then winding this elastic member *g* about both arms.

To use the toy, it is thrown in the air to a height of about twenty or thirty feet and obviously when it is thrown the elastic member is released and will unwind. This is so designed as to unwind when the toy reaches a height of about twenty or thirty feet; it will then disconnect the arms and permit the spring *d* to open the closure. This will permit the parachutes *f* to fall out, which will open up and drift slowly to the ground. When it is desired to use the toy again the parachute is merely picked up and folded together and placed in the closure as before.

One of the main features of my parachute is that the same is so constructed that it will quickly open when the same is released from the closure. I form this parachute of very flexible material, such as very thin paper. I take the blank *i*, as shown in Fig. 6, crease and fold in each corner along the dotted line *j*. I then fold these turned in flaps back along the dotted line *k*. These creases and folds are put in by the manufacturer and the parachute is very readily folded up again due to these sharp creases which have been placed in the flexible material. I provide a relatively stiff spider *m* which is provided with a plurality of arms, the end of each arm being secured to a corner of the flexible body portion of the parachute. This relatively stiff spider has secured at the center a weight *n*. When the parachute is released this weight pulls down on the spider and opens up the parachute, as shown in Fig. 5, and the parachute drifts slowly to the ground.

The main idea is such a toy is to have a parachute which will open almost immediately upon being released from the closure which has been thrown in the air. I

accomplish this by a combination of two principles: First, when the cover halves fly open it creates a suction between the two halves and tends to partially open the parachute and also throws the parachute out of the closure. The second aid in opening the parachute is the fact that the weight n which is secured to the spider at the center is positioned so as to lie extended out from the center of the parachute, as shown in Fig. 2. This weight could be projected to one of the sides or one of the corners. The weight of this suspended weight is borne along one edge or one corner of the parachute and tends to weight this side down, as shown in Fig. 4, and tends to overturn the parachute and position the same in the correct position for opening the flexible part of the parachute. It is obvious that there are numerous ways of constructing this weight and of securing the same to the spider, but I find that a weight which is suspended from the spider at the center and adapted to lie to one side thereof when the parachute is collapsed, tends to open the parachute much more quickly.

My toy overcomes most of the disadvantages which are present in the prior art, wherein a cloth or flexible parachute member is crumpled up inside of a closure which flies open to release the parachute at a given time. It is found that a flexible parachute which is not folded properly does not open up very readily. Also the use of strings in a toy parachute prohibits the same from opening up quickly because the strings get tangled together. I have found that my parachute will open up generally in a fall of about eighteen inches. This is a much better performance than has been obtained with the use of the devices found in the prior art. Another advantage from folding these parachutes, as shown, is that the same may be folded flat and enables one to place a plurality of parachutes in one closure.

What I claim is:

1. In a toy, the combination of a flat closure constructed of two flat halves hinged together, means tending to yieldingly force the two halves apart, each half provided with an arm, said arms arranged to lie adjacent to each other when the closure is in closed position, and an elastic member secured to one arm and adapted to be wrapped around both arms to hold the closure in a closed position but permitted to unwind when released to allow the closure to open at a predetermined time for releasing the contents of the closure.

2. In a toy, the combination of a flat closure constructed of a pair of flat and relatively stiff members hinged together, means tending to yieldingly force the hinged mem-

bers apart, the said hinged members each provided with an arm, said arms arranged to lie adjacent to each other when the closure is in closed position, and an elastic member secured to one arm and adapted to be wrapped around both arms to hold the closure in a closed position but permitted to unwind when released to allow the closure to open at a predetermined time for releasing the contents of the closure.

3. In a toy, the combination of a book-shaped closure constructed of a pair of flat cardboard members hinged together, spring means tending to yieldingly force the hinged members apart, the said hinged members each provided with an arm, said arms arranged to lie adjacent to each other when the closure is in closed position, and an elastic member secured to one arm and adapted to be wrapped around both arms to hold the closure in a closed position but permitted to unwind when released to allow the closure to open at a predetermined time for releasing the contents of the closure.

4. In a toy, the combination of a closure constructed of a pair of flat and relatively stiff members hinged together, means tending to yieldingly force the hinged members apart, means for temporarily holding said closure in a closed position but arranged to automatically release at a predetermined time to permit the closure to open, and one or more collapsible parachutes held between said hinged members when the closure is held in closed position, said parachutes constructed of relatively light flexible material folded to lie flat when collapsed, whereby the suction created by the opening of said closure partially opens said collapsible parachutes.

5. A toy comprising an angularly shaped member of flexible material which is creased and folded in at the corners to form a collapsible parachute, a spider secured to the folded in corners of said parachute, and a weight secured to said spider which serves to open said parachute when the same is released and permitted to fall to the ground.

6. A toy comprising an angularly shaped member of flexible material which is creased and folded in at the corners, said folded in portions creased and folded outwardly to form a double fold, thereby forming a collapsible parachute, a spider having arms which are each secured to one of the folded corners of the said parachute, and a weight secured to said spider which serves to open said parachute when the same is released and permitted to fall to the ground, the said arms holding the corners of the parachute apart to prevent the collapsing of the parachute when falling.

7. A toy comprising an angularly shaped

member of flexible material the corners of which are creased and folded inwardly and then creased and folded back on themselves to form a collapsible parachute, a relatively stiff spider having a plurality of arms, each arm being secured to one corner of the collapsible parachute, and a weight arranged

to be suspended from the center of said spider which serves to open said parachute when the same is released and permitted to fall to the ground.

In testimony whereof I have affixed my signature.

ARTHUR C. HEMPEL.
